LOCK CYLINDER

Walter Edwin Best, Indianapolis, Ind., assignor to Best Lock Corporation, Indianapolis, Ind., a corporation of Delaware

Filed Apr. 14, 1966, Ser. No. 542,507
12 Claims. (Cl. 70—370)

ABSTRACT OF THE DISCLOSURE

A formed sheet-metal lock-cylinder or housing for a removable lock core. Three formed cup-shaped sheet-stock piece parts having front flanges are nested together with their front flanges interlocked to form a face flange and to prevent axial and rotational displacement of the parts. The outer cup forms a body for insertion in a lock-receiving bore, the intermediate cup or tub defines a shaped opening to receive an 8-shaped core, and the third piece part is a face member which covers the face flange and forms a seat for the front flange of the core. The core is locked in place by engagement of a key actuated retainer behind the rear face or shoulder of the tub. A throw member for driving a secondary locking mechanism is rotationally mounted in the bottom wall of the outer cup.

This invention relates to a lock cylinder for mounting a lock core in a door or the like for control of a secondary locking mechanism such as a rim night latch or mortise lock.

It is the object of my invention to provide an improved lock cylinder adapted to accommodate a key-removable interchangeable core, which will be of light weight and great strength and may be made of a variety of metals as desired, with different parts of different metals if desired; which will require a minimum of machining operations, and which may be composed in its entirety of one or more piece parts produced from sheet stock by stamping or drawing operations.

In a preferred embodiment of the invention, the lock cylinder is composed of piece parts formed from sheet stock, and comprises an outer body wall for insertion in a door bore or cavity, joined at the front to a face structure forming the exposed portion of the cylinder and providing a radial flange to lie against the face of the door, and the body is preferably provided with internal or external threads for engagement by screws or other retaining means. The face structure desirably defines a counter-sunk opening to pass the body of the lock core and to seat and retain its front flange, and a transverse wall spaced rearward from the face structure is formed to pass the rearward portion of the lock core and to provide a stop behind which is locking lug or other retainer on the core engages to prevent core removal except by proper key retraction of the locking lug. Desirably, the cylinder also provides a second transverse wall spaced rearward from the core-retaining wall, in which is mounted a drive mechanism for interconnecting the lock core to operate the secondary locking mechanism.

The accompanying drawing shows a preferred embodiment and illustrates the invention.

In such drawing:

FIG. 1 is a front elevation of a lock cylinder embodying the invention;

FIG. 2 is an axial section view taken on the line 2—2 of FIGS. 1 and 3, and showing a drive mechanism for operating a secondary locking mechanism such as a rim night latch;

FIG. 3 is a rear elevation of the structure shown in FIGS. 1 and 2;

2

FIG. 4 is a sectional view of the drive mechanism, taken on the line 4—4 of FIG. 2;

FIG. 5 is a fragmental sectional view taken on the line 5—5 of FIG. 2;

FIG. 6 is a perspective view of a key-removable interchangeable core;

FIG. 7 is a fragmental axial sectional view similar to FIG. 2, taken on the line 7—7 of FIG. 8, showing a modification in which the cylinder is provided with external threads and the drive mechanism is of the type required on a mortise cylinder; and

FIG. 8 is a rear elevation of the modification shown in FIG. 7.

A preferred form of key-removable lock core 40 is shown in FIG. 6. This comprises a body 42 having the configuration of two intersecting parallel cylinders, commonly referred to as a "figure-8" shape, with a narrow radial flange at the front, and having a flat front core face 41. A retaining lug 45 projects laterally from the side of the body at the rear, and is retractable by a control key 46. The core includes a key-operated rotor having rear drive openings for engagement with a throw member as described below.

The lock cylinder of FIGS. 1—5 comprises a deep-drawn cup 30 having a cylindrical side wall 29, a rear transverse wall 28, and a front radial flange 31. The front radial flange contains two diametrically opposite notches 37 and 39, in the plane of FIG. 2.

Within the front of the cup 30 is nested a second deep-drawn member, conveniently referred to as a tub 32. This has a flange 33 at its front edge which lies against the radial flange 31 of the cup 30 and has a tab 38 which fits into the notch 37 of the flange 31 to orient the tub rotationally in the cup 30. The tub 32 has a drawn section of oval cross section, oriented with its long axis extending diametrically across the cylindrical cup 30; and the bottom of the tub 32 forms a transverse wall 47 intermediate the length of the cup 30.

A cylinder face member 34 in the form of a shallow drawn stamping nests within the drawn section of the tub 32. It has a radial face wall which lies against the flange 33 of the tub 32 and is joined at its edges to a rearward-extending axial flange 35 which is crimped under the flanges 31 and 33 of the cup 30 and tub 32 to secure the three nested parts together. The crimped-under edge 36 of the face member, at 69, is staked into such notch 39 of the rim 31 to fix the face member 34 against rotation with respect to the cup 30.

The bottom wall of the face member 34 and the bottom wall of the tub 32 are each provided with figure-8-shaped openings 43 and 44, adapted to closely receive and pass the similarly-shaped body 42 of the lock core 40 shown in FIG. 6. The drawn portion of the face member 34 comprises a side-wall 34' which, in cross section, has the same figure-8-shape as the opening 43, but is sufficiently larger to receive the flange at the front of the core 40. As the result, the opening 43 in the bottom wall of the face member 34 is bounded by a narrow, inward-extending flange 43' which forms a forwardly-presented seat or shoulder for the rear surface of the front flange of the lock core 40.

FIGS. 1, 2 and 5 show that the front wall of the face member 34 extends in a flat plane from the outer circular edge of flange 35 inward to the line at which it joins the side wall 34' of the drawn portion of the face member. The depth of the drawn portion may be substantially equal to or slightly greater than the axial thickness of the front flange of the lock core 40, so that when the lock core 40 is inserted in the cylinder, the core face 41 will be coplanar with, or slightly recessed from the face of the cylinder, for protection of the core.

The position of the rear wall 47 of the drawn tub 32 is

such that it forms a shoulder immediately in front of the retaining lug 45 of the lock core 40 when such core is inserted in the cylinder with its face flange seated in the drawn cavity of the face member 34. The generally oval configuration of the drawn section of the tub 32 locates its side wall 32' closely about the drawn side wall 34' of the face member at the end portions of the oval, but the mid portions of the oval need not curve inward with the side wall of the face member and are desirably flat as shown. One flat mid section of the side wall 32' of the tub 32 lies close to the point 49 at which the retaining lug 45 of the lock core 40 will engage behind the bottom wall 47 of the tub 32 and serves to strengthen that bottom wall as a retaining stop for the lock. Other shapes may be used to obtain such reinforcing relationship.

For the purpose of retaining the lock cylinder assembly in place in its mounting, its rear wall 28 is pierced at two spaced points to form squirts 68 which are internally threaded for the reception of retaining screws.

As noted above, the lock-core receiving openings 43 and 44 in the bottom walls of the face member 34 and tub 32 have the configuration of two intersecting circles. Coaxially with one of such circles, the bottom wall 28 of the cup 30 is provided with a circular opening for mounting the drive mechanism. Such drive mechanism comprises a throw member having two parallel legs 50 bent forward from a plate 51 of circular configuration and of a diameter somewhat larger than the opening in the wall 28. The plate 51 lies against the front face of the wall, over such opening, and is provided with two diametrically opposite notches 57, angularly spaced 90 degrees from the legs, 50, which receive tabs 52 integral with the side walls of a mounting cup 53. At angularly spaced points from such tabs 52, portions of the side walls of the cup 53 are bent outward to form tabs 56. The mounting cup 53 is rotatably received in the opening in the cap bottom wall 28 with its tabs 56 against the outer face of such wall 28 and with its tabs 52 extending through the wall 28 and the notches 57 of the plate 51. The tabs 52 are bent inward over the face of the plate 51 to secure the cup 53 and the throw members 50 together as a rotatable assembly in the wall 28.

The bottom wall of the cup 53 is provided with a cross-shaped hole 54 for the reception of the hooked front end of a tail piece 55, at 90° locations. The tail piece 55 serves as the drive link between the cylinder assembly and a secondary locking mechanism such as a rim night latch, not shown.

In use, the lock cylinder of FIGS. 1-5 is inserted in a cylindrical hole in a door or the like, with the crimped-under edge 36 of its front flange lying against the face of the door adjacent the edge of the hole, and is secured in place by screws threaded into the squirts 68. The tail piece 55 is inserted in an appropriate position in the cross-shaped hole 54 and its free end is engaged in the secondary locking mechanism, such as a rim night latch mounted on the opposite face of the door. A key-removable lock core 40 as shown in FIG. 6 is inserted through the openings 43 and 44 of the face member 34 and tub 32, with its rear drive-openings engaged over the legs 50 of the throw member. Such insertion of the core 40 carries its front flange into the drawn section of the face member and against the seat formed by the inward-extending flange about the opening 43 of the face member 34, and locates the face of the core 40 substantially coplanar with or slightly behind the front face of the cylinder. During this insertion, the control key 46 will have been actuated to retract the locking lug 45 of the lock core 40 to permit the figure-8 configuration of the core body 42 to pass through the correspondingly-shaped openings 43 and 44. When the core 40 is fully seated in the cylinder assembly, the lug 45 will lie close behind the inner wall of the tub 32, at the point 49, and when the control key 46 is turned to removal position, the lug 45 will be projected outward to lie behind such point 49 of

the inner wall 47 of the tub 32, and the lock core 40 will be secured in place in the cylinder. With such a core in place, the only exposed surfaces will be those of the face member 34 and the face 41 of the lock core 40. The surface of the face member 34 can be made of material selected primarily for appearance, while the other parts of the cylinder may be made of material selected for strength or other characteristics.

In the modification shown in FIGS. 7 and 8, the front portion of the cylinder 67 is the same as the modification of FIGS. 1-5. In the drive mechanism, a cam 59 is used instead of the tail piece 55. The cam 59 is mounted flat against the end wall of the cup 66 of the cylinder 67, and is connected through a hole in such wall to a throw member 60. This has two forward-extending legs bent up from its base plate 62, and at angularly spaced points, two tabs 61 are bent downward from the plate 62 to extend through the hole in the bottom wall of the cup 66 and into holes 63 in the cam 59. The ends of the tabs 61 are staked at 64 to fix the cam 59 and throw member 60 together as a rotatable assembly in the bottom wall of the cylinder 67.

Threads 65 on the outside of the cup 66 permit the cylinder 67 to be screwed into a mortise lock in conventional manner.

The size and length of the cup 30 in the modification of FIGS. 1-5 and of the cup 66 in the modification of FIGS. 7 and 8 can, of course, be varied to suit the intended installation and the lock core 40 which is to be used with the cylinder. Likewise, the position of the intermediate wall formed by the bottom of the tub can be at any longitudinal location within the cylinder to match the longitudinal position of the lug or other retaining means of the lock core which is used; and the drawn sections and openings in the face plate and tub can be shaped to fit about the lock core used. I also contemplate that the core-retaining intermediate wall can be formed in the cylinder by means other than the use of a tub 32, and that tub and face member may be used in combination to support a lock core 40 with other structure different from the cup 30 or even along without the cup 30. The invention contemplates such changes as may be made within the scope of the patent claims.

I claim as my invention:

1. A lock cylinder comprising an assembly including two interfitted elements formed of sheet stock, such assembly having a front peripheral face flange adapted to lie in a plane against the face of a door, said interfitted elements each having a drawn side wall extending normal to the plane of said face flange and having a transverse member, said elements having abutting portions which prevent relative movement in one direction, one of said elements providing a forwardly-presented shoulder in fixed position spaced from the front of said face flange and forming a stop for engagement by a rearwardly-presented shoulder on a lock core, the other of said elements providing a rearwardly-presented shoulder in fixed position spaced from the forwardly-presented shoulder and forming a stop for forward engagement by a lock core retaining means to prevent forward removal of the lock core, at least one of said transverse members including a sheet-stock wall defining an opening for the longitudinal reception of the body of the lock core and shaped to prevent rotation of the body, and means on said cylinder for engagement with retaining means to secure said cylinder in the place relative to the door.

2. A lock cylinder as in claim 1 comprising a drawn cup providing an outer side wall and having an integral peripheral flange at its front end which at least partially forms said front face flange.

3. A lock cylinder as in claim 2, in which said rearward facing shoulder is on a transverse wall supported intermediate the length of said drawn cup, and said drawn cup has a bottom wall spaced rearward from said transverse wall.

4. A lock cylinder as in claim 3 with the addition of

drive mechanism rotatably mounted in said bottom wall of the cup.

5. A lock cylinder as in claim 4, in which said drive mechanism comprises a sheet-stock part having a base plate bearing against one face of said cup bottom wall and forwardly bent throw legs extending therefrom, and a retainer member bearing against the opposite face of said cup bottom wall and secured to said base plate through a hole in said cup bottom wall.

6. A lock cylinder as in claim 2, comprising a tub having a front flange overlying and rotationally oriented with respect to the rim of said drawn cup, said tub having a section extending longitudinally within said cup, said rearwardly presented shoulder being provided by said tub, and means to secure said cup and tub together.

7. A lock cylinder as in claim 6, in which said tub section has a side wall closely adjacent to and supporting said rearwardly presented shoulder stop.

8. A lock cylinder as in claim 6, comprising a face member having a face wall overlying the flanges of said cup and tub, the edges of said member being bent rearward and crimped under said flanges to secure the parts together, said face member having an inwardly disposed seat forming said forwardly-presented shoulder stop for engagement by a rearwardly-presented shoulder on the 25 lock core.

9. A lock cylinder as in claim 8 adapted to receive a lock core having a body in the configuration of two intersecting parallel cylinders with a similarly shaped flange at the front thereof and a retractable retaining lug rearward 30 thereof, in which lock cylinder the said face member forms a recessed seat shaped to receive said lock-core flange, and said tub has a section of oval cross section in which the recessed seat portion of the face member is nested, and said cup has a rear wall provided with an opening coaxial with one of the parallel cylinders of the lock core, in which a drive mechanism is rotationally 35

mounted for operatively connecting the lock core to secondary locking mechanism.

10. A lock cylinder as in claim 1, comprising a drawn tub having a radial flange wall which at least partially forms said face flange, and having a drawn section extending rearward therefrom, said rearwardly-presented shoulder stop being supported by said tub drawn section.

11. A lock cylinder as in claim 10 comprising a face member having a face wall overlying said tub flange wall and secured thereto, and having a recessed seat portion nested in said tub drawn section and forming said forward-presented shoulder.

12. A lock cylinder as in claim 11 in which the face flange is circular, said recessed seat has the configuration of two intersecting circles offset in diametrically opposite directions from the center of the face flange, and said tub drawn section is of oval cross section with the long axis thereof in the diametrical direction of such offset.
